US0D1105045S

(12) **United States Design Patent** (10) **Patent No.:** **US D1,105,045 S**
(45) **Date of Patent:** **** Dec. 9, 2025**

(54) **DISPLAY MODULE FOR DISPLAY DEVICE**

(71) Applicant: **LG Display Co., Ltd.**, Seoul (KR)

(72) Inventors: **HoChun Yi**, Seoul (KR); **YongBum Kim**, Seoul (KR); **KiHwan Son**, Seoul (KR); **Ilsup Yoon**, Seoul (KR); **Kyungju Kim**, Seoul (KR); **Dong Jin Seo**, Seoul (KR)

(73) Assignee: **LG DISPLAY CO., LTD.**, Seoul (KR)

(**) Term: **15 Years**

(21) Appl. No.: **29/934,735**

(22) Filed: **Mar. 27, 2024**

Related U.S. Application Data

(63) Continuation of application No. 29/837,413, filed on May 5, 2022, now Pat. No. Des. 1,026,880, which is

(57) **CLAIM**

The ornamental design for a display module for display device as shown and described.

DESCRIPTION

FIG. 1 is a front, left perspective view of the display module for display device showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a front, right perspective view thereof, shown in an alternate state; and,

FIG. 9 is a front, left perspective view thereof, shown in an alternate state.

The broken lines in the drawings depict portions of the display module for display device that form no part of the claimed design.

1 Claim, 9 Drawing Sheets

Related U.S. Application Data

a continuation of application No. 29/738,455, filed on Jun. 17, 2020, now Pat. No. Des. 955,374, which is a continuation of application No. 29/664,135, filed on Sep. 21, 2018, now Pat. No. Des. 890,152.
